UNITED STATES PATENT OFFICE.

DÉSIRÉ MUREAU, OF PARIS, FRANCE.

DRAWER-LOCK.

1,240,760.

Specification of Letters Patent. Patented Sept. 18, 1917.

Application filed May 13, 1914. Serial No. 838,355.

To all whom it may concern:

Be it known that I, DÉSIRÉ MUREAU, citizen of the Republic of France, residing at Paris, France, have invented certain new and useful Improvements in Drawer-Locks, of which the following is a specification.

This invention has for its object to provide a drawer lock which is adapted to be operated by means of a number of draw bars, and which comprises a combination mechanism which can be varied at will.

A lock constructed according to this invention affords a high degree of safety against unauthorized opening and it is characterized not only by its general arrangement, but more particularly by the construction of a reversible plunger bolt with one or more heads; by the construction of the operating draw-bars which it comprises and which can be rendered operative or inoperative at will, without taking the lock to pieces in any way, for the purpose of rapidly varying the combination which serves to open the lock and allow the drawer to be pulled out.

A suitable construction of a lock constructed according to this invention is illustrated by way of example in the accompanying drawings, in which:

30 Figure 1 is an end elevation of a drawer provided with the improved lock, showing a row of draw-bars (for example, six) which are normally covered by a guard which allows the fingers of the operator to act upon 35 the said draw-bars in the direction capable of opening the lock.

Fig. 2 is a plan showing the mechanism of the lock, exposed by the removal of the lock plate that forms a cover hinged to the 40 upper part of the lock casing.

Fig. 3 is a vertical cross section on the line A—B of Fig. 2.

Fig. 4 is an under side view of the lock showing more especially the mechanism for 45 striking the bell or gong comprised therein.

Fig. 5 shows in longitudinal elevation the reversible plunger bolt.

Fig. 5^a shows the bolt, Fig. 5, in cross section on line C—D.

50 Fig. 6 shows separately in longitudinal section and in plan one of the operating draw-bars of the lock.

Fig. 7 shows this draw-bar with its operative portion in a different position.

55 Figs. 8 and 9 show modifications of the

mechanism for actuating the operative part of the draw-bars.

Fig. 10 shows a device for locking the operative elements of the lock.

The bolt of the lock shown in the example, has heads 5, 5 (two are shown in the drawings) mounted to slide in plunger fashion in guides 6, 6 (Figs. 2, 3 and 5). These heads are acted upon by a spring 7 which has a constant tendency to return 65 them into the projecting position. The guides 6, 6 are fixed to an axle 8 provided with journals at its ends. The mechanism comprising the axle 8, the guides 6, 6 and the heads 5, 5 is to be referred to hereafter 70 as a whole under the collective name of reversible plunger bolt. The mere pressure of the drawer provided with a lock is sufficient to cause the heads 5, 5 to enter of themselves into their guides by means of their inclined surfaces; these heads are adapted to shoot back automatically again into their 75 sockets and thus close the lock.

The bolt as a whole is mounted in the lock casing 4 in such a manner that it can revolve 80 on its own axis and thus allow when it is not engaged, its heads to rotate and consequently move out of engagement by the pull exerted upon the drawer in order to open same.

85 The engagement of the bolt in its closing position is effected by means of a rod 9 (Fig. 3) against which abut shoulders formed on the guides 6, 6. This engaging rod is suitably mounted in the sides of the lock casing, and when the lock is closed, the said rod rests freely on the top of blocks 10 provided on the draw-bars 1.

These blocks have each the shape of a pyramid (Fig. 6) whose narrow inclined opposite and symmetrical surfaces constitute the planes over which the rod 9 can slide in the case of those blocks which have been moved into the proper position. A stirrup-shaped piece 11 connects the pyramid block 95 of each draw-bar to the branch 12 of the latter in such a manner that by mere pushing in one direction or the other the said block will be moved either forward as shown in Fig. 6 or backward as shown on Fig. 7, 100 that is to say its apex will be moved respectively into or out of the vertical plane of the rod 9.

The axle of the stirrup-shaped member 11 is mounted in a corresponding notch in the 110

branch 12, and a spring 13 acting upon it has a tendency to keep it in engagement and consequently to keep the block 10 in one or other of the positions (forward or backward) allotted to it. In the forward position of the blocks, the engaging rod 9 remains raised so long as the corresponding draw-bars have not been pulled, while when in the rear position they do not oppose any resistance to this pull under the influence of the pulling of those draw-bars on which the blocks are in the forward position.

The forward portion of the draw-bar, namely the portion situated under the drawer-pull 2, is bent in the shape of a hook for the purpose of being grasped and pulled by one finger of the hand of the operator.

A pin 14 screwed to the lower part of the draw-bar near the block 10 extends through the bottom of the lock casing and is situated in front of a cross piece 15 (Figs. 3 and 4) which is capable of rocking at 16 on the said casing. All the pins 14 arranged in line bear upon the cross piece 15.

To this cross piece 15 there is pivoted a hook 17 (Fig. 4) subjected to the opposing action of a spring 18 having a constant tendency to return the cross piece back toward the line of pins 14. A boss 19 of the hook 17 engages a projection 20 of the cross piece 15 for the purpose of transmitting to the latter the entire action of the spring 18. Normally the hook 17 engages a part 21 rocking on a fixed axle and carrying a hammer 22 adapted to strike a bell or gong shown in dotted lines in Figs. 3 and 4. On any one of the draw-bars 1 being pulled the cross piece 15 will rock and the hook 17 will act violently upon the hammer 22 which will then strike the gong. On the return of the cross piece 15 the hook 17 will yield slightly under the influence of the hammer carrier and will resume its position engaging the latter ready for another operation.

If desired a damper 23 arranged by the side of the gong (Fig. 3) may be applied against the latter so as to prevent it from sounding. This damper is operated from the outside by means of a knob 24 on the front of the drawer below the draw-bars. It allows of deadening at will the striking of the gong which accompanies every operation or attempted operation of the lock but with this peculiarity that since this operating knob is arranged among a number of other knobs of similar appearance it will only be known by the person who is authorized to open the drawer.

Another knob 25 similarly disposed among other knobs allows of acting upon a lever or member 26 (Figs. 11) designed to lock the cross piece 15 and thus prevent any operation of the lock.

When the cross piece 15 is not locked and

if the draw bars are pulled, the blocks 10 of which have been moved into their forward position (Fig. 2) the operating rod 9 will be depressed. Said operating rod 9 normally prevents the rotation of the guides 6 around the axles 8 in such a manner that any sudden pull exerted with the intention of opening the drawer is immediately overcome by said rod 9; if, however, the rod is pressed down through the normal action of the draw-bars 1, no resistance will be offered to the rotation of the respective guides 6 which under the influence of a pull exerted and in consequence of the supports of the heads 5, 5, swings toward the rear and permits the opening of the drawer.

When the drawer is opened, the locking bolt returns automatically into its locking position so that the draw-bars 1 which were actuated are immediately returned into their normal positions by the spring 18 acting upon the cross piece 15. The heads 5 of the locking bolt are mounted upon springs 7 located within a recess formed at the rear end of said locking bolt, so that they give way under the pressure of the drawer and fall back again into the recess of the bolt. It will be noted that if the damper 23 has remained raised, the pull exerted upon these draw-bars will cause the gong to sound, and the same will happen if the other draw-bars have been pulled instead of the proper ones, so that this gives an audible alarm of the fact that an attempt has been made to open the lock.

Instead of the knobs provided below the draw-bars holes may be provided into which there may be engaged at will a movable pin adapted to operate the damper 23 and the locking member 26.

In any case the draw-bars which have been pulled, when released by the operator, are returned into their normal position by the spring 18 which has been stressed by the pulling of the said draw-bars. The action of this single spring may be reinforced by means of leaf springs provided for each draw-bar.

From the foregoing it will be understood that it will be easy to cause any desired draw-bars to become operative for opening the lock so that any desired combination may be produced. For this purpose it is merely necessary to lift the cover 3 and to operate the pyramid blocks 10 by simply moving them forward or backward. When moving forward they become operative; when moving backward they become inoperative. As will be seen the changing of the combination may be effected instantaneously without taking the lock apart in any way.

The blocks of the draw-bars may have the modified shape shown at 10' in Figs. 8 and 9, that is to say, instead of being adapted to slide they are made reversible and

mounted on a pivot 14'. The pivot which is of square cross section extends below the draw-bar and performs at the same time the function of the pin 14 for actuating the cross piece 15. The pressure exerted by the latter will then have the effect of securing the operative or inoperative position of the block 10' imparted to the latter.

Having now particularly described and ascertained the nature of my said invention and in what manner the same is to be performed, I declare that what I claim is:

1. A combination lock for drawers, comprising in combination, a casing, a bolt pivotally mounted on said casing, a series of draw-bars slidably mounted in said casing, blocks secured to one end thereof, and means slidably mounted in said casing coacting with said blocks and means to retain said blocks in one of two positions, substantially as described.

2. A combination lock for drawers, comprising in combination a casing, a bolt pivotally mounted on said casing, a series of draw-bars slidably mounted in said casing, handles formed at one end thereof, actuating members secured to the inner end of said draw-bars and a transverse bar slidably mounted in said casing coacting with said bolt and actuating members to retain said bolt in one of two positions, substantially as described.

3. A combination lock for drawers, comprising in combination a casing, a bolt pivotally mounted on said casing, a series of draw-

bars slidably mounted in said casing, handles formed on one end of said draw-bars, blocks secured to the other end of said draw-bars, said blocks being adapted to swing in an arc of 180°, a transverse rod slidably mounted in a vertical plane in said casing, intermediate said blocks and said bolt, said blocks being operative in one of two positions and adapted to coact with said bar to retain said bolt in one of two positions, substantially as described.

4. In a combination lock for drawers, a casing, draw-bars slidably mounted in said casing each provided with a depression intermediate its ends, springs secured to the front wall of said casing, and to the front part of said draw-bars, stirrups above the depressed part of said draw-bars, blocks pivotally mounted in said stirrups, a transverse rod slidably mounted in the walls of said casing, an axle journaled in the side walls of said casing, guides on said axle, heads sliding in said guides and a spring secured to the central guide tending to return said heads into their closing position, said rod normally resting upon said blocks and during operation to engage shoulders of said guides, substantially as described and for the purpose set forth.

In testimony whereof I affix my signature in presence of two witnesses.

DÉSIRÉ MUREAU.
